Primary Examiner—Melvin B. Feifer
Attorney, Agent, or Firm—Terry M. Gernstein[57] **CLAIM**

The ornamental design for a adjustable golf putter, as shown and described.

DESCRIPTION

FIG. 1 is a perspective view of the adjustable golf putter embodying the design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom view thereof;

FIG. 7 is a perspective view of an alternative form of the putter head; and,

FIG. 8 is a perspective view of another alternative form of the putter head.

The shaft has been omitted for ease of illustration from FIGS. 7 and 8 and it is understood that the remaining views of said embodiments are the same as FIGS. 2, 3, 4 and 5.

FIG. 4.

FIG. 2.

FIG. 5.

FIG. 3.

FIG. 6.
